UNITED STATES PATENT OFFICE.

JOHN WHITTAKER, OF ST. LOUIS, MISSOURI.

SAFE, VAULT, &c.

SPECIFICATION forming part of Letters Patent No. 425,280, dated April 8, 1890.

Application filed April 17, 1889. Serial No. 307,561. (No model.)

To all whom it may concern.

Be it known that I, JOHN WHITTAKER, of St. Louis, Missouri, have made a new and useful Improvement in Safes, Vaults, and other 5 Constructions Requiring Protection against Burglars and other Improper Interferers, of which the following is a full, clear, and exact description.

The object of the improvement is to provide a way of constructing or arranging safes, vaults, and other constructions, whereby greater protection against burglars and other improper interferers is secured than has heretofore been attainable; and the improvement 15 consists in the novel structure, combination, and operation, hereinafter fully set forth, as well as pointed out in the claim.

Figure 1 is a perspective view of a safe having the improvement applied to the interior of the walls thereof, and also an outside reservoir; Fig. 2, a horizontal cross-sectional view of the safe on the line 2 2, Fig. 4, looking down; Fig. 3, a vertical transverse section through the rear wall of the safe on the line 3 3, Figs. 2 and 4, looking to the rear; Fig. 4, a vertical longitudinal sectional view on the line 4 4, Figs. 2 and 3, looking to the left, as shown; Figs. 5 and 6, front and side elevations, respectively, of a safe having one 25 form of the improvement applied by inclosing the sides, top, and rear of the safe in a cage of pipes. Fig. 7 represents a side elevation of a safe having the improvement and connected with a reservoir placed outside of the apartment containing the safe by a pipe. Figs. 8, 9, 10, and 11 are cross-sections of variously-constructed walls of safes embodying 30 the improvement in various forms.

The same letters of reference applied to the 40 drawings denote the same parts.

A, Figs. 1, 2, 3, and 4, represents a safe embodying the improvement; B, the top; C and D, side walls; E, the rear wall; F, the bottom, and G the door of the safe; b' c' d' e' f' g', respectively, the outer side of the parts last 45 above named, and b' c' d' e' f' g' the inner side thereof, respectively; b² and f², protecting-pipe arranged in two courses in both the top and bottom shell of the safe; c², d², and 50 g², thin flat protecting-chambers constructed, respectively, in the walls C D and door G of the safe; e², a single course of protecting-

pipes placed in the rear wall E of the safe; H, fireproofing material of any of the usual kinds in the shell of the safe; I I', reservoirs 55 for the protecting substance placed, respectively, either inside or outside or both inside and outside of the safe and connected by the pipes i i', respectively, with the protecting chambers and pipes in the shell of the 60 safe; g³, reservoir for the protecting substance in the door of the safe and connected with the chamber g² by the pipe g⁴; g⁵ and e³, cocks whereby to charge the chambers, pipe, and reservoirs of the safe with the protecting substance; g⁶ and b³, cocks for the escape 65 of air from said receptacles as they are being charged.

K, Figs. 5 and 6, represents a cage of protecting-pipe inclosing the sides, top, and back 70 of the safe A', which is otherwise unprotected. The pipe may be fastened in any suitable manner to the floor, and it may be applied also under the safe, if desired. The door may be furnished with inside chambers, as shown 75 in Fig. 4, or an outside door formed of pipes distinct from those forming the cage may be provided. By this arrangement unprotected structures may easily be protected. Fig. 7 is a safe embedded in masonry. 80

Figs. 8, 9, 10, and 11 are cross-sections of some variously-constructed walls of safes embodying the herein-described improvement in various forms, in which n represents sheet metal, preferably iron or steel of, say, one-half inch 85 thick, more or less, l a space of, say, one or two inches, more or less, between some of the sheets of said metal, forming chambers to be charged with the protecting substance, as heretofore described, and m a space filled 90 with customary fireproofing material, which may be arranged to be next to either the outside or the inside of the shell of the safe, according to the idea of the builder.

Figs. 2, 3, and 4 are intended to show various 95 forms and arrangements of protecting-chambers that may be employed, but not to convey the idea that the variety should be applied in one structure. The protecting-chambers may be constructed of any suitable shape 100 and size. They may be flat and thin and placed parallel to and nearly coextensive with the length and width of the door or that part of the shell in which they are placed. They

may be formed by spacing apart the sheets of metal of which the shell of the safe is constructed when constructing it, or they may be formed of pipe, as shown. In the use of 5 pipe for this purpose the parallel courses thereof should be placed as close to each other as practicable or as may be deemed necessary for security, and as many as practicable of the protecting-chambers of each safe should, 10 preferably, be connected together, so that in case of a puncture or fracture of a chamber the quantity of the protecting substance subject to escape from said puncture or fracture would be larger than if the chamber were not 15 connected with the others.

The above remarks have reference to structures having only what may be termed one "layer" or "series" of chambers. A greater 20 degree of protection may be secured by constructing two or more of the said series of chambers instead of but one series and by arranging the several series in layers parallel to each other and to the surface of the shell or door, whereby an outer series becomes a protection 25 to an inner series, which presents an additional obstacle to an intruder after the outer series had been punctured and emptied.

This last above-mentioned construction is illustrated by Fig. 11, in which l^1 l^2 represent 30 two parallel protection-chambers, forming part of two series, as described. In this feature of the improvement each series of connected protecting-chambers should communicate exclusively with its respective reservoir of the protecting substance, whereby the power and effectiveness of a series of protecting-chambers is much increased. Said reservoirs may be located in the shell or door of, or in the interior of, or at any suitable place 35 exterior to, the safe; and in case of employing an external reservoir, as above described, increased security may be obtained by locating said reservoir at some concealed or well-protected point more or less remote from the 40 apartment containing the safe, which arrangement is shown in Fig. 7, in which D^2 represents a side of a safe embodying the improvement and embedded in masonry, G^2 being the front and E^2 the back of the safe, and 45 p^2 a pipe concealed in masonry leading from the interior chambers of the safe to the reservoir I^2 , located in a separate apartment P above the floor p .

The herein-described reservoirs are receptacles for a reserve supply of the protecting substance, which, in addition to that which may be in the chambers, is constantly at hand ready to spring instantly into action when the structure is attached; hence by connecting 55 a described reservoir to a series of chambers said chambers may be of smaller capacity than would be advisable in the event that no reservoir were used, and the chambers may then contain the protecting substance in its 60 gaseous form only, while that contained in the reservoir is in the liquid form.

It is desirable to have the chambers and

reservoirs located and arranged so that when the chambers are punctured that portion of the protecting substance which escapes will 70 be in its gaseous form only, and that portion which retains its liquid form will remain in the chambers or the reservoirs until the reduction in pressure allows it to volatilize while therein. With this end in view the 75 pipes connecting the chambers with the reservoirs should be arranged so as to draw the protecting substance from the reservoirs at the top thereof, thereby allowing the gaseous portion to pass out thereof and the liquid to 80 remain until it vaporizes therein.

The chambers and reservoirs should be provided with means for the escape of air therefrom while they are being charged. The charging-cocks should, when practicable, be 85 placed on the inside of the safe or other structure to which the improvement is applied.

The protecting-chambers should preferably be located so as to especially guard those parts which are most likely to be attacked, as the 90 locks and hinges.

The doors of a safe or analogous structure may have a reservoir attached to the inside thereof, or the chambers therein may by means of jointed pipe or other equivalent means be 95 connected on the interior of the safe or structure with some of the chambers in the shell.

The improvement is not limited in its application to safes. It may also be advantageously applied to the protection of compartments and houses. Constructions lacking ordinary burglar-proof guards may by the application of this improvement be rendered "burglar-proof." For instance, an ordinary room may by this means be made burglar-proof by applying the protecting-chambers in the form of pipe to the windows and doors thereof and to any further extent deemed necessary. It is of course understood that the pipe is to be charged in the manner described.

By the application of this improvement a burglar-proof structure may be constructed almost entirely of pipe; but in all applications of the protecting-chambers in the form of pipe or otherwise to the outside of a structure said chambers should be so placed as to bar access to the portion of the structure which they are designed to protect, and said chambers should be adapted in form, position, and extent to the nature, form, and size of the structure they are designed to protect.

The reservoir I^2 in Fig. 7 is charged through the pipe i^10 , which preferably leads nearly to the bottom of the reservoir. The valves i^{20} i^{30} control the escape of the ammonia or other protecting substance from the reservoir.

The cage K of protecting-pipes is intended to have its pipes filled with the gas or liquid under compression, and the pipes are arranged 130 so close together that a drill could not cut into the body of a safe without cutting one or more of these communicating-tubes, thereby permitting the gas or liquid to expand or es-

cape and overpower the person attempting to break the safe. In this construction the receptacles of the gas or liquid must be outside the safe and a door must be constructed in the surrounding cage-tubing.

5 I claim—

In a safe or vault having a shell or frame consisting of an outer and inner wall, and a suitable packing between said walls, of chambers, tubular or otherwise, embedded in said packing and having pipes or nozzles projecting into the interior of the safe or vault and

provided with cocks within said interior, so that the chambers can discharge therein, and reservoirs arranged to contain a suitable gas 15 or liquid under compression and having tubular connection with the said embedded chambers, substantially as specified.

Witness my hand this 15th day of March, 1889.

JOHN WHITTAKER.
